HANS WILHELM CHRISTIAN SCHRÖDER, OF LUBECK, GERMANY, ASSIGNOR, BY MESNE
ASSIGNMENTS, TO HEINRICH OTTO DRÄGER, OF LUBECK, GERMANY

INHALING APPARATUS

Application filed June 11, 1926, Serial No. 115,175, and in Germany June 13, 1925.

The present invention refers to improvements in apparatus for inhaling gases particularly for anesthetic purposes in which the stream of gas is started from time to time by hand and regulated either also by hand or automatically by the operation of the lungs. Under certain circumstances such temporary starting of the stream of gas independent of the regulation proper was of late, as is well known, left to the patient himself, because now-a-days anesthetic gases are known, which are mixed with oxygen, at such proportions that they can never be dangerous, and moreover because the novel narcotic apparatus are so constructed, that they allow of any degree of anesthesia between relaxation or full consciousness and unconsciousness. The semi-self-control of the device by the patient is especially desirable in such cases, in which no serious narcosis is required but merely a reduction of sensibility, for instance when pains arise periodically, particularly birth-throes. In such cases it must be taken into account that not all patients have the necessary clear reflection for self-operation or that frequently they lose their mind, when overwhelmed with pains, so that they are no longer in a position to do the proper thing for cutting off the stream of gas.

With the present invention the above stated circumstances are taken into account in this way, coincidentally with starting the stream of gas a controlling member is set to operate, which automatically cuts off the stream of gas after the passage of a certain period of time, say one to two minutes. For a woman it is a very great relief if other than the manipulation for starting the stream no more attention or operation on her part is required and when she may rest assured that the duration of the narcosis is suited to the circumstances and regulated automatically.

In the drawing an apparatus is shown by

way of example for carrying out the invention.

Fig. 1 is a diagrammatical elevation partly in section of the complete narcotic apparatus.

Fig. 2 is a similar view of one part of the apparatus in a position in which the stream of gas is cut off.

Fig. 3 is a modification of a means for operating the apparatus.

The apparatus comprises a steel cylinder ⁵⁵ *a* for the narcotic gas having a pressure reducing valve *b* and a second steel cylinder *c* for the oxygen, also provided with a pressure reducing valve *d*. Both pressure reducing valves in the position of the apparatus shown in Fig. 1 are open. The pipes *e* and *f* conduct the gases to the casing *g'* of the controlling valve *g*. Within this casing the two gases are mixed when the piston valve *y* is in the position shown in the drawing, Fig. 1, and by the pipe *h* the mixture is allowed to enter the breathing bag *i* through the pipe *h*. The patient inhales the gas from the bag *i* through the pipe *k*, the pipe or hose *l* and the mask *m*, exhaling through the non-return valve *n*. ⁶⁰ When the piston *y* is in the position in Fig. 2 the stream of gas coming from the pipe *e* and that coming from the pipe *f* are shut off, and also the pipe *k* is closed. The patient then breathes only atmospheric air through the non-return valve *o*, which in this position is ⁶⁵ free to operate, while it is shut off during the narcosis period by the controlling valve *g* in the position shown in Fig. 1. ⁷⁰

When owing to a pain an anesthetic is required the piston valve *y* must be brought into its working position illustrated in Fig. 1, so that the mixture of gas is allowed to enter the mask. This is accomplished by lifting the piston *p* within the cylinder *q*, either ⁸⁰ by pulling the cord *r* or by allowing compressed oxygen to enter the cylinder *q* beneath the piston *p* through the pipe *f*. For the last named operation the valve *s* is provided, which by the aid of a push-button *t* can be ⁸⁵ ⁹⁰

opened to allow a sufficient amount of oxygen to quickly flow into the cylinder q . As long as the push-button t is not operated the valve s remains closed. By a pull on the cord r atmospheric air flows by way of the suction valve u into the cylinder q to allow the piston p and the piston y to be raised. The push-button and the cord r may be operated according to need or choice. In both instances the piston p , acting as a yielding wall, moves upwardly. At the same time the spring v arranged above the piston p will be compressed and at the final part of the stroke the arm w acts to move the piston valve y into its working position, Fig. 1. When the cord or the push-button is released the spring v will operate to return the piston p back to the bottom of the cylinder, whereby at the same time the air or oxygen escapes slowly in one to two minutes by way of the fine opening x acting as a brake or throttling nozzle retarding the return of the piston. The piston p represents a movable element subjected to a force, such as gravity and the action of the spring v , which imparts to the element a movement with a predetermined speed. When the piston reaches a predetermined position in the course of its movement, shortly before it reaches its position of rest and dead point at the bottom of the cylinder the arm w engages a shoulder y' on the piston rod y' , so that the controlling valve g will also be shifted to its inoperative position as shown in Fig. 2. From this moment the patient only inhales atmospheric air.

The starting of the stream of gas, while operating the time-controlling means, instead of being effected by the cord r or push-button t may be accomplished by any other means, for instance a lever z , Fig. 3. The starting device may also be made to operate independently of the time-controlling device in such way that the patient may after pulling on the cord either let it go or hold it fast. Instead of the time controlled device illustrated any other suitable time-controlling device may be provided which can be operated or released by the pull on the cord, for instance a fan acting like an air brake or any well known clock-work, which after a certain time automatically comes to rest. In this case initially the gas stream will be allowed to run and at the end cut off again.

It appears advisable to arrange the gas controlling valve, by positioning the piston in such manner, that at the end of the narcosis period the connection with the reservoir bag is interrupted, and only such with the atmospheric air is established. In this instance the feeding of the gas to the bag may be continued for a few seconds. The object of this is to have a filled bag at disposal at the beginning of the next narcosis for the initial respiration.

65 The described releasing operation may also

be used for anesthetic apparatus, in which the feeding of the gas is dosed by the lungs automatically, as well as for apparatus having a closed circuit of a gas stream and the binding of the carbonic acid during the narcosis period. 70

I claim:—

1. In an apparatus for administering anesthetic inhalation gases, the combination with means controlling the flow of said gases to the respiration organs, of a fluid reservoir having a throttling outlet, a movable wall in said reservoir, a connection from said movable wall to said controlling means whereby an actuation of the latter to start the flow of gases will coincidentally operate said movable wall, the latter retarding the return movement of said controlling means to thereby automatically delay the cutting off of said flow for a predetermined period of time. 75

2. In an apparatus for administering anesthetic inhalation gas, the combination comprising manually adjustable valve means controlling the flow of said gas, resilient means connected with said adjustable means and tending to re-set the same into the inoperative position in which the flow of said gas is stopped, and retarding means operatively connected with said resilient means so as to retard the re-setting movement for a predetermined period of time. 80

3. In an apparatus for administering anesthetic inhalation gas, the combination comprising manually adjustable valve means controlling the flow of said gas to the organs of respiration, resilient means connected with said adjustable means and tending to re-set said regulating means into the inoperative position in which said flow is substantially stopped, and a pneumatic device operatively connected to the regulating means so as to retard its return into the inoperative position for a predetermined period of time. 100

4. In an apparatus for administering anesthetic inhalation gases, the combination comprising valve means controlling the flow of said gases to the respiration organs, means for setting the valve into an operative position, a movable element and means for imparting thereto a movement with predetermined speed, said element being connected with said valve means so as to be started by the setting operation of said valve means and to react at a predetermined point of said movement on the valve means in order to re-set the same into an inoperative position, thereby stopping said flow. 105

5. In an apparatus for administering anesthetic inhalation gas, the combination comprising regulating valve means adapted to be manually set into an operative position in which a flow of said gas is conducted to the organs of respiration, and to be automatically re-set into an inactive position in which a flow of non-anesthetic gas is conducted to 115 120 125 130

said organs, a movable element and means for imparting thereto a movement with predetermined speed, said element being so connected with said regulating valve means as to be started coincidentally with the manual setting operation thereof and to perform the automatic re-setting when it reaches a predetermined position in the course of its movement.

5 In testimony whereof I have signed my name to this specification.
